SMOKING PIPE

William Appel, Harrison, Ark.

Application September 8, 1941, Serial No. 410,109

3 Claims. (Cl. 131—201)

This invention relates to smoking pipes and the object thereof is to provide a smoking pipe equipped so that the influx of air into the bowl; the passage thereof therethrough and into the shank and therethrough; is divided and forced into controlled multiple channels of draft, thereby eliminating the gathering of moisture at the bottom of the mass of tobacco in the bowl of the pipe and also greatly reducing the temperature of the smoke, by forcing same into contact with the surfaces of multiple channels in the stem portion of the shank.

The invention, together with its objects and advantages, will be best understood from a study of the following description taken in connection with the accompanying drawing, in which like characters of reference have been employed in the several figures, to designate identical parts and wherein:

Figure 1 shows the assembled pipe as cut through on the line of the longitudinal axis thereof, showing the shank element in elevation, in the stem-forming portion of the shank of the pipe;

Figure 2 shows a plan view of the floor portion of the minor lower end of the bowl of the pipe;

Figure 3 shows the shank element in perspective view;

Figure 4 shows the stem-forming portion of the pipe, cut through the line 4—4 of the Figure 1;

Referring now in detail to the several figures, the pipe proper, as shown in Figure 1 is composed of five elements.

The pipe may be constructed from any preferred material or from a combination of such materials.

The bowl 1 (Figure 1) is formed as a separate element; its major upper portion extending upwardly from the top edge margin of a cavity in the enlarged, bowl-end portion of the shank 2, the other end, the mouth piece end of which is adapted for engagement with the inner end of the mouth piece 3.

The minor lower portion of the bowl 1 is adapted to be housed in spaced relation to the floor of the cavity in the bowl-end of the shank 2.

The construction employed for the engagement of the bowl 1 with the shank 2 is optional. Any one of numerous well known means for such connections, in fixedly attached or in removable relation of the bowl to the shank may be employed.

The cavity 4 is bored in the major upper, tobacco containing portion of the bowl. The diam-

eter of this cavity is varied to conform to the size and the style of the pipe designed and also has its depth from the top edge margin down established by these factors. From this point of depth cavity 4 is continued downwardly, at a lesser diameter, thus forming the cavity 5 in the minor lower, tobacco-free portion of the bowl. This operation creates the annular, inwardly extending shoulder 6. This shoulder functions as a support for an annular screen diaphragm 7 which covers the cavity 5 and forms a floor for the cavity 4.

Through the floor of the minor lower portion of the bowl 1 are let the perforations 8—9—10 (Figure 2). These perforations are specifically located and spaced for cooperative relation with the termini of conduits in the stem-forming portion of the shank 2. The perforation 8 extends downwardly from a point below and adjacent to the inner edge of the annular shoulder 6 and on a line with the medial portion of the floor of the cavity 5, and the perforations 9—10 respectively, are located one on each side of and adjacent to this medial line and are in similar relation to the annular shoulder 6 on the side wall of this cavity that is opposite to the perforation 8. The spacing of the perforations 8—9—10 is designed to come within the circumference of the diameter of the floor of the cavity in the bowl-end of the shank for cooperation with the termini of conduits in the stem-forming portion of this shank. The bowl-end of the shank 2 has a cavity therein which is adapted for housing the minor lower portion of the bowl 1 with the under surface thereof being in spaced relation to the floor of this cavity, and also for holding, intermediate said under face and in closely spaced relation thereto, and the above mentioned floor surface, the end portion of a shank element. The bore in the stem-forming portion of the shank 2 is dimensioned to receive the shank element and hold same in snug engagement with the inner wall of the bore.

The numeral 11 (Figure 3) designates this shank element; its longitudinal dimension equals, or may, to a minor extent, exceed the space intermediate the mouth-piece-end margin of the shank 2 and the far wall of the cavity in the bowl-end thereof. Into the side portions of the periphery of the shank element 11 and parallel to its longitudinal axis, grooved channels are let and into one of the spaces of the periphery, intermediate these grooved channels and on the medial line of this space another such like grooved channel is let.

These grooved channels are herein designated 8a-9a-10a, to emphasize the close cooperation thereof with the perforations 8-9-10, as will be shown hereinafter. The termini of the grooved channels 8a-9a-10a at the mouth-end 12 are deepened and converge toward the center of this end. For facilitating the withdrawal of element 11 from the stem of the shank the pin 12a is provided.

From a point on the grooved channel 8a, inwardly from the edge margin of the end 13 the cutaway portion 13a is formed with its contour similar to the lower inner portion of the bowl of a pipe. The lowest point in this cutaway portion coincides with a transverse line from grooved channel 9a to the grooved channel 10a. The under face of the end 13 and of the cutaway portion 13a is adapted for contacting engagement with the floor and the lower inner wall portion of the cavity in the bowl-end of the shank 2.

The pipe is assembled as follows: the annular screen diaphragm 7 is entered into the cavity 4 and forced to its seat on the annular shoulder 6. The minor lower portion of the bowl 1 is placed into the cavity in the bowl-end of the shank 2 with the perforation 8 above the opening of the bore of the stem into the bowl-end cavity of the shank 2 and in line with the longitudinal center thereof. The shank element 11 the end 13 foremost and cutaway portion 13a uppermost is entered into the bore of the stem-forming portion of the shank 2 and brought inwardly to abut the end 13 against the lower portion of the far wall of the cavity in the bowl-end of the shank. The mouth piece 3 which has its inner end portion adapted to house the pin 12a is attached by means of any of the well known methods for such engagements.

In this assembly the grooved channels 8a-9a-10a are in cooperation with the inner wall of the bore of the stem-forming portion of the shank 2 and thus form conduits through this stem. The bowl-end termini of these conduits lie in spaced, staggered relation to each other in the cutaway portion 13a and under and in closely spaced relation to and in substantial alignment with the perforations 8-9-10, respectively, in the floor of the minor lower portion of the bowl 1. This relative position of the elements of the pipe to each other and of the termini of the conduit 8a to the perforation 8 and the conduit 9a to the perforation 9 and the conduit 10a to the perforation 10 is accomplished when the bowl 1 is positioned on the shank 2. If a detachable junction of these two elements is desired, a stop point is provided which prevents the displacement of the bowl 1, either, when the pipe is assembled or by accidental displacement after being assembled.

It will be observed that, in a pipe constructed as herein described, when suction is applied at the mouth piece 3 to ignite the tobacco contained in the upper portion of the bowl 1, the strongest influx of air thereinto is forced by this suction to points on the mass of the tobacco in the bowl that lie directly above the perforations 8-9-10 and adjacent to the inner surface of the bowl wall. Three separate streams of smoke are thus produced. The normal burning of tobacco being by means of glowing coals, the coals, following the strongest line of draft downwardly trap moisture intermediate said lines of burning coals and dry same as condensation occurs. This manner of burning the tobacco in the bowl eliminates the collection of moisture at the base of the mass of tobacco, which occurs when gravity

and central suction draft normally force such concentration of it.

The forcing of the smoke through the conduits 8a-9a-10a in the stem-forming portion of the shank 2 also aids the cooling thereof, and results in a more comfortable use of the pipe.

While I have herein illustrated what I believe to be a preferred and practical embodiment of my invention, it is obvious that various changes and alterations might be made in the general form of the parts described, or of materials employed, without departing from my invention and hence I do not limit myself to the precise details set forth but consider myself at liberty 15 to make such changes and alterations as fairly fall within the spirit and scope of the appended claims.

I claim:

1. In a pipe, comprising a separate bowl, a shank and a mouth piece, one end of the shank fitted for engagement with the inner end of the mouth piece and the other end thereof being enlarged and having a cavity adapted for housing the lower portion of the bowl of the pipe and for 20 engagement with the bowl in fixedly attached or removable relation therewith, said bowl having an open major portion, a cavity therein of a given diameter and having integral therewith a closed end minor lower portion, a cavity therein being 25 an extension, at a lesser diameter, of the cavity in said major upper portion of said bowl, an inwardly extending annular shoulder intermediate said cavities, this shoulder being adapted for supporting an annular diaphragm, an annular dia- 30 phragm on said shoulder forming a floor for the cavity in said major upper portion and a cover for the cavity in said minor lower portion of the bowl of the pipe, the closed end margin of the minor lower portion having let through its floor 35 portion specifically located and spaced perforations and said minor lower portion being adapted for being housed in the enlarged end portion of the shank and an element in the shank having a cutaway portion adapted to lie in the bowl end 40 of the shank and conduits extending longitudinally of the element, terminating in said cutaway portion, the under face of the closed end of the bowl being closely spaced relative to the upper face of said cutaway portion and the 45 perforations therein being in closely spaced relation and in substantial alignment with the termini of complementary conduits in the shank 50 of the pipe.

2. In a pipe, comprising a separate bowl, a shank and a mouth piece, one end of the shank fitted for engagement with the inner end of the mouth piece and the other end thereof being enlarged and having a cavity adapted for housing the lower portion of the bowl of the pipe and for 55 engagement with the bowl fixedly attached or in removable relation therewith, said bowl having an open major upper portion with a cavity therein of a given diameter and having integral therewith a closed end minor lower portion, a cavity therein being an extension, at a lesser diameter, of the cavity in said major upper portion, said bowl having an inwardly extending annular shoulder intermediate said cavities this shoulder being adapted for supporting an an- 60 nular diaphragm, an annular diaphragm on said shoulder forming a floor for the cavity in said major upper portion and a cover for the cavity in said minor lower portion of the bowl of the pipe, the closed end margin of the minor lower portion thereof having let through its floor por- 65

70

75

tion specifically located and spaced perforations and said minor lower portion being adapted for being housed in the enlarged end portion of the shank, and an element in the shank adapted to fit snugly into the stem-forming portion of said shank, this element having in the side margins of its periphery, parallel with its longitudinal axis grooved channels and having in one of the spaces of its periphery intermediate said grooved channels another such like grooved channel and the termini of the grooved channels in one end of the shank element being adapted for cooperative relation with a conduit in the mouth piece of the pipe, said shank element having a cut-away portion of similar contour to the lower inner portion of the bowl of the pipe in its other end portion, the termini of the grooved channels in this end of the shank element lying in spaced, staggered relation to each other in said cutaway portion, and said cutaway end portion extending into the bowl end of the shank with its upper face closely spaced relative to the under face of the closed end of the bowl of the pipe and the perforations therein being in closely spaced relation and in substantial alignment with the

termini of channels in the stem-forming portion of the shank of the pipe.

3. A pipe, comprising a separate bowl, shank and mouth piece, said bowl having its minor lower portion extending into a cavity in the bowl end of the shank, a shank element fitted snugly into the stem-forming portion of said shank, grooved channels in the periphery of said shank element cooperating with the inner wall of said stem-forming portion, to form conduits there-through said shank element having a cutaway portion extending into the cavity in the bowl end of the shank, the upper surface of said cutaway portion being in closely spaced relation to the under face of the minor lower portion of the bowl of the pipe, the floor of said minor lower portion having perforations closely spaced and in substantial alignment relative to the termini of the conduits in said stem-forming portion to form draft channels for drawing smoke into and from the space therebetween and for drawing smoke through the conduits extending through said stem-forming portion to the mouth piece of the pipe.
